[57] CLAIM

The ornamental design for a revolver support clip, as shown and described.

DESCRIPTION

FIG. 1 is a side elevation view of the present clip shown in position on a typical revolver in phantom lines.

FIG. 2 is a side elevation view of the revolver clip.

FIG. 3 is a side elevation view of the other side of the revolver clip from that shown in FIG. 2.

FIG. 4 is a top plan view of the revolver clip shown in the position of FIG. 2.

FIG. 5 is a top plan view of the revolver clip shown in the position of FIG. 3.

FIG. 6 is an end elevation view looking into one end of the revolver clip.

FIG. 7 is an end elevation view looking into the other end of the revolver clip.
